UNITED STATES PATENT OFFICE.

DUANE F. SWARTWOUT, OF LOS ANGELES, CALIFORNIA.

DESIGN FOR A SIGNAL-LAMP CASING.

Application filed August 8, 1928. Serial No. 27,745. Term of patent 3½ years.

To all whom it may concern:

Be it known that I, DUANE F. SWARTWOUT, a citizen of the United States, and resident of city of Los Angeles, State of California, have invented a new, original, and ornamental Design for a Signal-Lamp Casing, of which the following is a specification, reference being had to the accompanying drawing, forming a part hereof.

Figure 1 is a front end view of the casing.

Figure 2 is a side elevation.

Figure 3 is a cross-section on line 3—3 of Fig. 2, to illustrate the contour of the casing.

I claim:

The ornamental design for a signal lamp casing, substantially as shown.

Signed August 1st, 1928, Los Angeles, California.

DUANE F. SWARTWOUT.
